UNITED STATES PATENT OFFICE.

JOSEPH WALKER, OF BELLEVILLE, KANSAS.

WEATHER-STRIP.

SPECIFICATION forming part of Letters Patent No. 396,181, dated January 15, 1889.

Application filed May 26, 1888. Serial No. 275,133. (No model.)

To all whom it may concern:

Be it known that I, JOSEPH WALKER, a citizen of the United States, residing at Belleville, in the county of Republic and State of 5 Kansas, have invented a new and useful Improvement in Weather-Strips, of which the following is a specification.

My invention relates to improvements in weather-strips, having for its object to provide 10 a simple, cheap, and effective device to prevent wind and moisture from penetrating between the door (or window) and the casement; and it consists in a certain novel construction and combination of devices, fully set forth 15 hereinafter in connection with the accompanying drawings, wherein—

Figure 1 is a perspective view of a door provided with the improved weather-excluding devices. Fig. 2 is a perspective view of 20 the door, looking at its lower edge. Fig. 3 is a vertical sectional view of the door. Fig. 4 is a horizontal sectional view of the same. Fig. 5 is a detail view of one of the sheet-metal holders which are employed to engage 25 the strips. Fig. 6 is a plan view of the sill. Fig. 7 is a detail view of the hinge.

Referring to the drawings by letter, A designates the casement of the door, the sill B of which is provided with a longitudinal 30 drip-groove, b; and C designates the door, which is hinged to one side of the casement by means of the sliding joint-hinges D D. These hinges consist of the stationary straps E E, which are secured to the casement and 35 are provided with the rigid knuckles e e, and the swinging straps F, which are secured to the door and are provided with the knuckles f, vertically movable on the pivot-pins G. The lower stationary knuckles in the hinges 40 are provided at their upper ends with the semi-circular notches e', and the movable or sliding knuckles f are provided with the depending semicircular projections f' to fit in the notches e' when the door is in its closed position.

It will be evident from the above that as the free edge of the door strikes the casement the door will drop slightly, as the projections engage the notches, and in order to allow 50 the door to swing open freely it will be necessary to slightly raise it to disengage the said projections from the notches.

The edges of the door are provided with longitudinal grooves H, on both sides of which are arranged the channels I I, the said 55 groove in the hinged edge of the door being, however, inclined slightly, for a purpose to be described.

The holder K is composed of sheet metal, and consists of the flat roll k, engaging 60 the edge of the flexible strip L, and the lateral flange k' which is formed integral with the roll. The rolls of the holders are arranged in the above-mentioned grooves in the edges of the doors, and the flanges are 65 arranged flat against the edges of the door, and may be secured thereto in any suitable or preferred manner. The holder at the hinged edge of the door being arranged in an inclined groove, as described, the flexible strip 70 which is engaged in the holder will also be inclined, so that when the door is closed the strip will be bent over against the side of the casement and received in the channel I, and will not be doubled or crushed, as would be 75 the case if the said strip were arranged perpendicularly to the edge of the door.

The hinge is so constructed (as before explained) as to drop the door as the free edge thereof strikes the casement, so that the flexible strip on the lower edge is also bent over and compressed against the sill.

M M represent anti-friction rollers, (three or more in number,) which are mounted in castings N N, secured in recesses in the lower 80 edge of the door, and shallow sockets O O are formed in the sill to receive the lower sides of the rollers when the door drops, as described. The inner sides of these sockets are beveled up to the upper surface of the sill, so that 85 when the attempt is made to open the door the rollers successively travel up the said beveled sides of the sockets and gradually raise the door sufficiently to disengage the projections from the notches of the hinges, 90 and before the inner roller (or the roller adjacent to the hinged edge of the door) leaves the sill the said projections are out of alignment with the notches, and the door swings 95 freely with its lower edge out of contact with the carpet. Thus there is no difficulty experienced in either opening or closing the door, the weather-strips being brought into 100 the operative position only when the door is

entirely closed, and therefore there is no unnecessary wear on the said strips.

The drip-groove before mentioned, which is located under the lower edge of the door 5 when the latter is closed, is in a position to receive the moisture which drops from the door and prevent water from being driven under the same, and small channels P are formed in the sill to conduct away the water 10 which accumulates in the groove.

It will be evident that the compressed strips at the edges of the door form impassable barriers to the entrance of the wind and rain which is driven against the door.

15 Having thus described my invention, I claim—

1. The combination, with a door mounted on sliding joint-hinges, of the flexible strips attached to the edges of the door and the 20 anti-friction rollers mounted on the bottom of the door, substantially as specified.

2. The combination, with a door having strips on its edges and mounted on sliding joint-hinges, of the anti-friction rollers 25 mounted on the lower edge of the door and bearing on the sill, and adapted to be received in beveled sockets in the sill, substantially as specified.

3. The combination, with a door frame or 30 easement and sill having a drip-groove, the channels leading from the groove, and the

beveled sockets of the door, the sliding joint-hinges having projections on the lower ends of their movable knuckles to engage corresponding notches in the upper ends of lower 35 stationary knuckles, whereby the door drops as its free edge strikes the easement, and the anti-friction rollers mounted on the lower edge of the door and bearing on the sill, and adapted to be received in the said sockets in 40 the sill, all constructed and arranged to operate substantially as and for the purpose hereinbefore specified.

4. The combination, with a door provided with grooves in its edges, of the holders K, 45 located in the grooves, and comprising the rolls k, formed by doubling the holder twice upon itself, and the flanges k', bearing on the edge of the door and formed integral with the rolls, and the flexible strips arranged at their 50 inner edges in the rolls and doubled on themselves therein, and projecting at their outer edges beyond the edge of the door, substantially as specified.

In testimony that I claim the foregoing as 55 my own I have hereto affixed my signature in presence of two witnesses.

JOSEPH WALKER.
